UNITED STATES PATENT OFFICE.

AUGUSTINE F. LITTLEFIELD, OF LYNN, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

MECHANISM FOR USE IN SHAPING SHOE UPPERS.

Application filed February 7, 1917, Serial No. 147,260. Renewed February 25, 1922. Serial No. 539,294.

To all whom it may concern:

Be it known that I, AUGUSTINE F. LITTLEFIELD, a citizen of the United States, residing at Lynn, in the county of Essex and State of Massachusetts, have invented certain Improvements in Mechanism for Use in Shaping Shoe Uppers, of which the following description, in connection with the accompanying drawings, is a specification, like reference characters on the drawings indicating like parts in the several figures.

This invention relates to shoemaking and particularly to the shaping of uppers including the removal of surplus upper stock from shoes.

Important features of the invention are to be recognized in a novel construction and arrangement of mechanism for trimming the marginal edge of an upper, and in a novel combination of trimming mechanism and means to position or to prepare the work for the trimming operation. In one important aspect, a feature of the invention consists in upper trimming mechanism constructed and arranged to co-operate in a novel manner with upper shaping means, for example end embracing wipers, whereby an upper is shaped over a form, to trim the margin of the upper while the upper is under control of the shaping means. Among its objects, the invention has in view the provision of means adapted for use to trim the margin of an upper which extends in transverse relation to the plane of the bottom of a form over which the upper is shaped, or to the plane of an insole, as for example on welt shoe work where the marginal portion of the upper is shaped to provide an upstanding flange adapted to be sewed to the lip or rib of the insole. For this purpose, the construction herein shown comprises a cutter which is movable to trim the margin of the upper in a plane substantially parallel to the bottom of the form or last or to the plane of the insole. More particularly, the illustrative embodiment of the invention comprises a power driven disk cutter which is movable to cut outwardly through the upstanding margin of the upper and to trim the upper on a continuous line extending from one side of the toe to the other side substantially in the plane of the outer face of the wipers. In a further novel aspect the invention provides means for determining the position of the

cutter relatively to the work, comprising in 55 the construction shown a member for engaging the insole to determine the plane of action of the cutter relatively to the rib of the insole.

A further feature of the invention consists in means for guarding the edge of the cutter. As herein shown the cutter is mounted on the lower end of a vertical shaft which is embraced by a sleeve that affords convenient means to be grasped by the operator in holding and guiding the cutter. The guard is mounted above the cutter to project normally beyond a portion of the acting edge of the cutter and a member connected to the guard extends in relation to the handle into 70 such position that the operator can manipulate the guard therethrough by means of the fingers grasping the handle.

A further feature of the invention consists in novel means for controlling the operation 75 of the trimming means, the construction shown comprising cutter operating means including a clutch through which rotary movement is imparted to the cutter while the cutter is in operative relation to the shoe or to the means, namely, the wipers, which hold the upper in position to be acted upon by the cutter, and disconnecting means automatically discontinuing driving of the cutter when the cutter is in inoperative relation to 85 the wipers or the shoe. As I am advised, moreover, it is new by this invention to provide means for supporting a shoe and holding the marginal portion of an upper in position for the surplus thereof to be trimmed 90 off, in combination with a rotary cutter adapted to trim off the surplus portion of upper material, and this constitutes a further feature of the invention.

Still other features of the invention consist in novel means for supporting a trimming device for movement relatively to a shoe, and in various details of construction and combinations of parts, all of which will now be described with reference to the accompanying drawings and pointed out in the claims.

Figure 1 of the drawings is a perspective view of one embodiment of the invention in a lasting machine of well known type.

Fig. 2 is a detail partly in section showing the trimming operation.

Fig. 3 is a side elevation, partly in sec-

tion, of the trimmer driving mechanism, and

Fig. 4 is a plan view of the rotary cutter with its guard.

- 5 The shoe is herein shown as supported for operation between a toe rest 2 and a hold-down 3. The toe lasting mechanism including the wipers 5 is employed for forming the upper material to the toe of 70
10 the last and compressing it upon the insole against the resistance offered by the supporting toe rest, which is raised and held in elevated position by connections with the power driving mechanism shown in Fig. 1
15 as shown and described more fully, for example, in Letters Patent No. 1,373,482 granted on April 5, 1921 upon an application of Matthias Brock. In their usual operation upon welt shoes the wipers gather 75
20 the upper inwardly over the feather of the insole and form it into a more or less up-standing flange between the edge face of the wipers and the rib or shoulder of the insole. The effect upon the upper is to present 80
25 it in approximately the position shown in the sectional view, Fig. 2.

The power driving mechanism includes a continuously running pulley 10 from which a belt extends upwardly to drive a pulley 12 located above and at the rear side of the machine and sustained by the usual tack hopper supporting bracket of the machine. Above the pulley 12 is located a pulley 14 arranged to drive a pulley 15 journaled in 85
30 the outer end of an arm 30 and having its spindle connected by a flexible shaft 16 to a stem or shaft 18 on the lower end of which is mounted a rotary disk cutter 20. The pulley 14 is journaled upon the upper end of a 90
35 shaft 13 extending through and fixed in the tack hopper bracket with its lower end extending below said bracket. The pulley 12 loosely journals on the sleeve of pulley 14 (Fig. 3).

40 The cutter is secured to the lower end of the shaft 18 by a stud or bolt 22, the lower end of which is rounded to adapt it for engagement with the tread face of the insole. This stud 22 may be caused to serve the purpose of gauging the height at which the cutter will trim the margin of the upper, as 95
45 illustrated in Fig. 2. The stem or shaft 18 of the cutter is shown as encircled by a sleeve 24 constituting a handle by which the operator can position and guide the cutter in trimming off surplus material progressively around the end of the toe.

A cutter edge guard 25 encircles the stem 18 closely adjacent to the top face of the 100
50 cutter and is preferably of a diameter to extend slightly beyond the periphery of the cutter and thereby protect the work from injury by accidental engagement with the cutter. This guard is supported by a vertical connecting member 26 fastened at the 105
55 upper end of the sleeve 24 and extending down the side of the sleeve in position to be engaged by the operator's fingers and allow the operator by such engagement to 110
60 retract the gage from and expose the portion of the edge of the cutter which he desires to have engage with the stock to be cut. The member 26 is preferably of spring metal and operates to return the guard automatically to working position when released 115
65 from pressure by the operator's fingers.

The arm 30 extends from the pulley shaft 13 and is swiveled so that said arm and the cutter can swing backwardly and away from the shoe into a position in which they are 80 out of the way during the lasting operation. The arm 30 is not directly connected to the pulley shaft 13 but is pivoted on a bracket 35 that has a base embracing and journaled on the lower end of pulley shaft 13 and supported upon the upper face of a washer fixed to the lower extremity of shaft 13. A spring 32, Fig. 3, sleeved on this washer with one end fixed to the washer and its other end secured to bracket 35, normally tends to return 90 the arm backwardly and away from the shoe. A spring 36 is interposed between the bracket 35 and arm 30 and operates to hold the arm normally in an upraised position, allowing the operator to lower the arm 95 and the cutter to the desired position for the work to be performed. Preferably also the pulley 14 is loose on the pulley shaft 13 so that it, and therefore the cutter, is normally idle. This reduces the danger of injury to 100 the work or to the workman which would arise from a continuously rotating knife, even when the knife is swung back to an inoperative position. A cone clutch, shown in section in Fig. 3, is provided for connecting 105 the pulleys 12 and 14. The inner member of the clutch is formed on the continuously running pulley 12, which pulley is mounted to have a short vertical movement on the shaft 13, being held in its depressed position by a spring 37. The pulley 12 has a lower face adapted to be engaged by rolls on the rear arms of a forked lever 40 pivoted on the bracket 35, the front arm of which lever extends under the swinging arm 110
115 30. A spring 42 is interposed between said arm and the underlying arm of the lever. A rigid finger 41 projects from the forked lever 40 approximately parallel to the arm 30, its end extending over a lug 43 laterally 120 offset from the arm 30. A set screw is carried by and depends from the end of said finger to be engaged by the lug 43 upon the upward movement of arm 30 positively to move downwardly the clutch operating end 125 of lever 40 to permit the clutch spring 37 to operate to throw out the clutch. The position of the lower end of the set screw may be adjusted to suit the strength of the spring 36 and to compensate for weakening of the 130

spring. The set screw and the spring 42 provide a connection between the depressible arm 30 and the clutch operating lever 40 so that when the arm 30 is depressed to bring the cutter into operative relation to a shoe on the toe rest, the lever 40 is rocked to close the clutch and cause the cutter to be rotated.

In the contemplated use of the machine, 10 a shoe is positioned upon the power operated toe rest and is clamped between said rest and the hold-down. The lasting wipers are then manipulated to form the upper around the toe of the last and are advanced 15 by the hand lever 7 to wipe the upper into the position shown in Fig. 2 and hold it for the operation of the cutter. When the upper has been satisfactorily lasted to the shape of the particular last upon which the shoe 20 is being made, the surplus portion of upper materials extending above the wipers can be accurately cut away on that particular shoe, thus leaving the shoe in the best possible condition for the welt sewing-on operation. 25 The operator now seizes the handle portion of the cutter and swings the cutter over the shoe bottom, depressing it until the gage 22 contacts with the insole inside of the gathered margin of the upper and then sliding 30 it forward and moving it around the toe to cause the cutter to trim off the upper materials at the elevation provided for by the gage stud 22. The cutter may thus be guided to cut outwardly through the flange 35 of the upper at one side of the toe and then to trim progressively round the toe to the other side. The guard 25 protects the edge of the cutter until the operator presses it back and uncovers the cutter for the trimming 40 operation. The closed wipers hold the upper against the thrust of the cutter and act as a shear blade to assist in insuring a clean cut by which the surplus material is entirely disconnected from the shoe. The 45 cutter preferably acts substantially in the plane of the top face of the wipers and if desired the wipers can be employed as a gage with reference to which the cutting can be done instead of employing the gage 50 22 for that purpose. When the trimming operation has been completed, and with the construction and organization illustrated this is done very quickly, the operator releases the cutter and it is swung back out of 55 the way by the action of spring 32, while spring 36 raises the cutter carrying arm 30 sufficiently to open the clutch.

The rotary disk cutter 20 illustrated herein I find particularly advantageous in that it 60 provides a series of spaced cutting edges or teeth which will bite into the upper materials and quickly cut through the double thickness of upper and lining. These series of teeth are formed by grinding out or otherwise forming in the face of the disk cutter

a series of spaced depressions with concaved outer edges which merge into the adjacent convex cutting edges of the disk and form a series of cutting teeth with clearance notches between the teeth of the series.

If desired, the surplus upper stock may be removed after the toe has been wired, and it may be also after the shoe has been removed from its support, the workman grasping the shoe and manipulating the cutter 70 to trim off the surplus materials in the manner previously described. While it is preferable to effect the trimming operation with the shoe supported as described because of the co-operative relations of the parts and 75 the convenience and saving of time afforded by such relations, it will be understood that, except as expressly stated by or necessarily implied from the claims the invention is not limited to these trimming and supporting 80 instrumentalities in combination.

While the invention is herein illustrated and described with particular reference to trimming off the surplus margin of the upper at the toe end of the shoe, it is not 90 intended thereby to imply any limitation with respect to such features of the invention as are clearly of utility irrespective of the particular portion of the shoe upon which the trimming operation is performed. 95

Having explained the nature of this invention and described a preferred embodiment of the same, I claim as new and desire to secure by Letters Patent of the United States:—

1. In means for removing surplus upper stock from the toes of shoes, the combination with means to gather the toe portion of an upper inwardly over the toe of an insole and hold it in position to be trimmed, 105 of a trimming cutter arranged to act in a plane substantially parallel to the plane of the insole on the stock so held to trim off the surplus margin of the upper by a continuous cut round the end of the toe from 110 one side to the other of the gathered material.

2. In means for removing surplus upper stock from the toes of shoes, the combination with toe embracing wipers constructed 115 and arranged to gather the toe portion of an upper and wipe it inwardly, of trimming means mounted for movement to trim off surplus upper by a continuous cut round the end of the toe substantially in the plane of 120 the top face of the wipers.

3. In means for removing surplus upper stock from the toes of shoes, the combination with means to gather the toe portion of an upper inwardly and hold it in position 125 to be trimmed, of a rotary cutter and means to drive it, said cutter being movable to trim the upper progressively around the toe adjacent to the gathering means.

4. In means for removing surplus upper 130

stock from the toes of shoes, the combination with wipers arranged to gather the toe portion of an upper inwardly and hold it in position to be trimmed, of a cutter movable to co-operate with the top of the acting edge of the wipers as a shear blade in trimming off surplus upper.

5. In means for removing surplus upper stock from the toes of shoes, the combination with means to hold a shoe upper substantially stationary, of a rotary cutter movable over the toe to trim off the surplus upper stock, and means to drive the cutter.

6. In means for removing surplus upper stock from the toes of shoes, the combination with means to position a shoe, of a rotary cutter movable over the toe to trim off the surplus upper stock, and a guard movable with the cutter and arranged relatively thereto for controlling the engagement between the cutter and the upper.

7. In means for removing surplus upper stock from the toes of shoes, the combination with means to position a shoe, of a rotary cutter adapted to be moved by the hand of an operator over the toe of the shoe, and a guard normally extending beyond a portion of the edge of the cutter and movable to uncover said edge for action on the upper.

8. In means for removing surplus upper stock from the toes of shoes, the combination with means to position a shoe, of a rotary disk cutter adapted to be guided by the hand of an operator around the toe of the shoe, and a guard normally extending beyond a portion of the edge of the cutter and movable by the fingers of the operator's cutter guiding hand to expose said portion of the edge of the cutter.

9. In means for removing surplus upper stock from the toes of shoes, the combination of a stem having a lower end shaped and adapted to engage the toe portion of an insole, a disk cutter rotatably driven about the axis of said stem, and a sleeve embracing the stem and adapted to be grasped by the hand of the operator in moving the cutter to trim the upper progressively around the toe.

10. In means for removing surplus upper stock from the toes of shoes, the combination of means to support a shoe, a rotary disk cutter, means to drive the cutter comprising a shaft to the end of which the cutter is attached, and a sleeve within which the cutter shaft rotates and which is constructed to adapt it to be grasped by the hand of the operator for guiding the cutter to trim the upper.

11. In means for removing surplus upper stock from the toes of shoes, the combination of means for supporting a shoe to be trimmed, means for supporting a trimmer normally out of operative relation to the

shoe, means for driving the trimmer, and a member connected with the trimmer and adapted to be grasped by the operator for moving the trimmer into operative relation to the work.

12. In means for removing surplus upper stock from the toes of shoes, the combination of means for supporting a shoe to be trimmed, means for supporting a trimmer normally out of operative relation to the shoe, means for driving the trimmer, means automatically disconnecting the driving means from the trimmer while the trimmer is out of operative relation to the shoe, and a sleeve connected with the trimmer and located adjacent thereto by which the operator can move the trimmer into operative relation to the work and cause the driving means to actuate the trimmer.

13. In means for removing surplus upper stock from the toes of shoes, the combination of a frame, a shoe support movably mounted in the frame, a toe trimmer movably carried by the frame, a driving member, and separately controllable connections from said member to the shoe support and to the trimmer.

14. In means for removing surplus upper stock from the toes of shoes, the combination of a frame, a shoe support movably mounted in the frame, a toe trimmer movably carried by the frame, a driving member, and separately controllable connections from said member to the shoe support to raise and lower it and to the trimmer to rotate it, said trimmer having a hand engaged member by which to move it over the shoe while it is rotating.

15. In means for removing surplus upper stock from the toes of shoes, the combination of a rotary trimmer, a bodily movable driving shaft on the end of which the trimmer is mounted, a sleeve embracing the shaft adjacent to the trimmer and adapted to be grasped by the operator's hand, a guard for the edge of the trimmer, and means operable by the fingers of the operator's hand to shift the guard relatively to the edge of the trimmer.

16. In means for removing surplus upper stock from the toes of shoes, the combination of a rotatable disk trimmer movable by the operator's hand over the work, an edge guard for the trimmer, and means controllable by the operator's hand for moving the guard to uncover the edge of the trimmer.

17. In means for removing surplus upper stock from the toes of shoes, the combination with means to support a shoe to be trimmed, of a trimmer comprising a rotary cutter, a shaft on the end of which the cutter is carried, a horizontally swinging arm in which the shaft is mounted, a support allowing vertical pivotal movement of the arm,

yielding means for holding the shaft carrying end of the arm normally upraised, and driving connections to the shaft automatically opened by the raising of the arm and 5 closed when the cutter is moved to operative position.

18. In means for removing surplus upper stock from the toes of shoes, the combination with means to support a shoe to be 10 trimmed, of a power operated upper trimmer supported for free manually effected movement about the toe portion of the shoe.

19. In means for removing surplus upper stock from the toes of shoes, the combination with means to support a shoe to be 15 trimmed, of a power operated trimmer supported for free manually effected movement about the toe portion of the sole, and means to guide said trimmer to act in a plane 20 substantially parallel to the plane of the sole.

20. In means for removing surplus upper stock from the toes of shoes, the combination with means to support a shoe to be 25 trimmed, of a trimmer supported for free manually effected movement about the toe portion of the shoe, power-operated driving means for said trimmer, and means operated by movement of the trimmer to connect 30 said trimmer with and to disconnect it from said driving means.

21. In means for removing surplus upper stock from the toes of shoes, the combination with means to support a shoe to be 35 trimmed, of a supporting member mounted for vertical movement, a power-operated trimmer supported by said member for free manually effected movement about the toe portion of the sole of a supported shoe, and 40 means normally effective to raise said supporting member and trimmer from the shoe.

22. The means for removing surplus upper stock from the toes of shoes, the combination with means to support a shoe to be 45 trimmed, of a supporting member mounted for movement toward and from the sole of a supported shoe, a power-operated trimmer supported by said member for free manually effected movement about the toe portion of 50 the sole of the shoe, and means operated by movement of said supporting member toward and from the shoe for connecting said trimmer with and disconnecting it from its power operating means.

23. In means for removing surplus upper stock from the toes of shoes, the combination with means to support a shoe to be 55 trimmed, of an arm mounted to swing in a plane substantially parallel with the plane 60 of the sole of the supported shoe and, additionally, to move toward and from the sole, and a power driven trimmer supported from said arm for free manually effected bodily movement about the toe portion of said sole.

24. In means for removing surplus upper

stock from the toes of shoes, the combination with means to support a shoe to be trimmed, of an arm mounted to swing in a plane substantially parallel with the plane of the sole of the supported shoe and, additionally, to move toward and from the sole, 70 a rotary disk cutter supported from said arm for free manually effected bodily movement about the toe portion of said sole, and power operated driving connections to said cutter including a clutch device operated by movement of said arm toward and from the sole of the supported shoe.

25. In means for removing surplus upper stock from the toes of shoes, the combination 80 with means to support a shoe to be trimmed, of a trimmer comprising a rotary disk cutter, a bodily movable shaft on the end of which the cutter is carried, a horizontally swinging arm supporting said shaft, a support 85 allowing vertical pivotal movement of the arm toward and from the sole of a supported shoe, power operated driving connections to said cutter shaft including flexible driving connections from said arm to said cutter 90 shaft and clutching means connected by vertical movement of the cutter connected end of said arm and cutter toward the sole of the supported shoe and disconnected by movement of said end of the arm away from 95 the sole, and yielding means for holding the cutter connected end of the arm normally moved away from the sole.

26. In means for removing surplus upper stock from the toes of shoes, the combination 100 of a support, and a power-operated trimmer depending therefrom and supported and arranged for free manually effected movement about the toe portion of the shoe sole with its cutting edge in a plane substantially parallel to the plane of said sole.

27. In means for removing surplus upper stock from the toes of shoes, the combination 110 of a trimmer, means for supporting the trimmer for manually effected bodily movement toward the sole of a shoe and about the toe portion of the sole with its cutting edge in a plane substantially parallel to the plane of said sole, and power-operated driving connections to said trimmer.

28. In means for removing surplus upper stock from the toes of shoes, the combination 120 of a trimmer, means for supporting the trimmer for manually effected bodily movement toward the sole of a shoe and about the toe portion of the sole, and power-operated driving connections to said trimmer effective to operate the trimmer upon movement of the trimmer into operative relation to the sole.

29. In means for removing surplus upper stock from the toes of shoes, the combination 130 of a support mounted for horizontal and vertical movement, a rotary disk trimmer depending from said support and arranged,

- when in trimming position, to present its cutting edge in a plane substantially parallel to the plane of the shoe sole, and power-operated driving connections to said trimmer including a flexible driving connection from said support to the trimmer. 5
30. In means for removing surplus upper stock from the toes of shoes, the combination of a support mounted for horizontal and 10 vertical movement, a rotary disk trimmer depending from said support, and power-operated driving connections to said trimmer including a flexible driving connection from said support to the trimmer and a clutching device controlled by vertical movement of the support. 15
31. In means for removing surplus upper stock from the toes of shoes, the combination of a support mounted for horizontal and 20 vertical movement, a rotary disk trimmer depending from said support, power-operated driving connections to said trimmer including a flexible driving connection from said support to the trimmer and a clutching device controlled by vertical movement of the support, and yielding means 25 normally tending to move said support into position to disconnect the trimmer from the source of power. 30
32. In means for removing surplus upper stock from the toes of shoes, the combination of a supporting member mounted for vertical movement, and a power operated trimmer supported by said member for free 35 manually effected bodily movement about the toe portion of a shoe sole. 35
33. In means for removing surplus upper stock from the toes of shoes, the combination of a supporting member mounted for vertical movement, and a power operated trimmer supported by said member for free 40 manually effected bodily movement about the toe portion of a shoe sole, means normally and yieldingly holding said supporting member vertically elevated, and means 45 operated by vertically downward movement of said member operatively to connect the trimmer with its power operating means. 50
34. In a machine of the class described, the combination with means for operating 55 upon shoe uppers including a power-driven element, of a trimmer operatively connected with said power driven element and supported for movement to trim the toe of a shoe upper positioned in co-operative relation to said operating means. 55
35. In a machine of the class described, the combination with means for operating 60 upon shoes including a shoe support, of a power driven shaft, and a trimmer arranged to be driven by said shaft and supported and arranged for manually effected movement over the toe portion of the sole of a supported shoe. 65
36. In a machine of the class described, 70 the combination with means for operating upon shoes including a shoe support and a power driven element, of a rotatable trimming tool arranged to be operated by said power driven element and supported and arranged for free manually effected movement about the toe portion of the sole of a supported shoe. 75
37. In a machine of the class described, the combination of means for supporting a shoe 75 and engaging the marginal portion of its upper to retain said portion of the upper in position relatively to the insole for the surplus thereof to be trimmed off, and a rotary cutter supported and arranged to trim 80 off the surplus portion of upper material. 80
38. In a machine of the class described, the combination of means for supporting a shoe and holding the marginal portion of its upper at one end of the shoe in position 85 for the surplus thereof to be trimmed off, and a power driven rotary cutter supported and arranged for manually effected movement over the end of the shoe in a plane to trim off said surplus of the upper material. 90
39. In means for removing surplus upper stock from the toes of shoes, the combination of a power driven rotatable trimmer mounted for movement over the work by the operator's hand, an edge guard for the trimmer, and 95 means controllable by the operator's hand for moving the guard to uncover the edge of the trimmer. 95
40. In means for removing surplus upper stock from the toes of shoes, the combination 100 with means to support a shoe to be trimmed, of a power operated trimmer supported for manually effected bodily movement over the toe portion of the shoe in a plane substantially parallel to the shoe sole to trim off 105 the surplus upper stock. 105
41. In means for removing surplus upper stock from the toes of shoes, the combination with means to support a shoe to be trimmed, of a supporting member mounted for vertical 110 movement, a power operated trimmer supported by said member for manually effected movement over the toe portion of the sole of a supported shoe, and means normally effective to raise said supporting member and trimmer out of its operating plane relatively 115 to the sole. 115
42. In means for removing surplus upper stock from the toes of shoes, the combination of a supporting member mounted for vertical 120 movement, and a power operated trimmer supported by said member for manually effected bodily movement over the toe portion of a shoe sole. 120
43. In means for removing surplus upper 125 stock from the toes of shoes, the combination with means to support a shoe to be trimmed, of a trimmer support and a power operated trimming cutter depending therefrom and supported and arranged for manually effect- 130

ed movement over the toe portion of the sole of a supported shoe with its cutting edge in a plane to trim off the surplus upper stock.

44. In means for removing surplus upper stock from the toes of shoes, the combination with means to support a shoe to be trimmed, of a trimming cutter, means for supporting said cutter for manually effected bodily movement toward the sole of a supported shoe and over the toe portion of said sole, and power operated driving connections to said cutter.

45. In means for removing surplus upper stock from the toes of shoes, the combination with means to support a shoe in position to be trimmed, of a trimming cutter supported for manually effected movement over the toe of the supported shoe and having means effective during such movement to guide said cutter in a plane substantially parallel to the sole.

46. In means for removing surplus upper stock from the toes of shoes, the combination with means to support a shoe in position to be trimmed, of a power operated rotary cutter supported and arranged for manually effected movement over the toe of the supported shoe and having means to engage the sole of the shoe during such movement to guide the cutter in a plane substantially parallel to the sole.

47. In mechanism for use in lasting shoes, the combination with means for gathering the end portion of an upper inwardly over the insole and holding it with its marginal edge upstanding from the insole, of trimming means comprising a cutter constructed and arranged to be positioned initially on the opposite side of said upstanding portion of the upper from the gathering means and to act in a plane substantially parallel to the plane of the insole to trim the margin of the upper.

48. In mechanism for use in lasting shoes, the combination with means for gathering the end portion of an upper inwardly over the insole and holding it with its marginal edge upstanding from the insole, of a power operated disk cutter arranged to operate in a plane substantially parallel to the plane of the insole to trim the upstanding edge of the upper.

49. In mechanism of the class described, the combination with end embracing wipers for gathering the upper of a shoe inwardly round the end of the shoe and holding it with its marginal edge upstanding, of trimming means comprising a cutter constructed and arranged to be positioned initially inside of the gathered margin of the upper and having a cutting edge directed oppositely to the inner edges of the wipers to trim off a portion of the margin of the upper extending above the top face of the wipers.

50. In mechanism of the class described,

the combination with end embracing wipers for gathering the upper of a shoe and holding it in gathered condition, of a power driven cutter arranged to be operated independently of the wipers to trim the margin of the upper while the upper is so held.

51. In mechanism of the class described, the combination with means for gathering the end portion of an upper and holding it in gathered position, of trimming means movable lengthwise of the edge of the upper to trim the margin of the upper progressively while the upper is so held.

52. In mechanism of the class described, the combination with means for gathering the end portion of an upper and holding it in gathered position, of a power driven rotary cutter movable manually along the marginal edge of the upper to sever it from the remainder of the upper stock.

53. In mechanism of the class described, the combination of a cutter adapted to be moved manually into position for trimming off the marginal edge of the upper of a shoe, and a guard movable with said cutter and arranged to be positioned normally in advance of the edge of the cutter, said cutter and guard being relatively movable against yielding resistance to permit the cutter to act upon the upper.

54. In mechanism of the class described, the combination with shoe positioning means, of a power driven device for trimming the marginal edge of the upper of the shoe, and means for supporting said device normally out of operative relation to the shoe while permitting it to be moved manually into operative relation to the shoe.

55. In mechanism of the class described, the combination with shoe positioning means, of a cutter for trimming the marginal edge of the upper of the shoe, means for operating said cutter, means for supporting the cutter for movement into and out of operative relation to the shoe, and mechanism controlled by said movement of the cutter for connecting it to and disconnecting it from its operating means.

56. In mechanism of the class described, the combination with shoe positioning means, of an upper trimming device, and means for supporting said device for movement at the will of the operator lengthwise and heightwise of the shoe into or out of position for trimming the marginal edge of the toe portion of the upper of the shoe.

57. In mechanism of the class described, the combination with means for holding a shoe substantially stationary, of an upper trimming device, means for supporting said device for movement at the will of the operator into or out of position for trimming off the marginal edge of the upper of the shoe while the shoe is thus held, and means for engaging the insole of the shoe to posi-

tion said device relatively to the plane of the shoe bottom.

58. In mechanism of the class described, the combination with shoe positioning means, of power driven upper trimming means, and means for supporting said upper trimming means for manual movement lengthwise of the edge of the upper to trim said edge progressively.

10 59. In mechanism of the class described, the combination with means for gathering and wiping the margin of an upper inwardly round the end of a shoe form, of a cutter supported by the machine independently of 15 said gathering and wiping means for movement in a direction substantially parallel to the plane of action of said means to sever the surplus margin of the upper from the remainder of the upper stock.

20 60. In mechanism of the class described, the combination with means comprising end embracing wipers for gathering the margin of the toe portion of an upper and forming it into an upstanding flange, of a cutter mounted for movement in such relation to 25 said upstanding flange as to sever the entire surplus margin of the upper round the toe from the remainder of the upper stock by a cut substantially in the plane of the top 30 face of the wipers.

61. In upper trimming means, a power driven cutter constructed for use to sever the surplus margin of an upper round the end of a shoe from the remainder of the 35 upper stock while said margin is held in gathered and overwiped position, and a support for said cutter adapted to be freely moved manually along the bottom of a supported shoe to present the cutter in position 40 to trim said margin.

62. In an upper shaping machine, the combination with means for gathering and wiping the marginal portion of the toe of an upper inwardly over the bottom of a form, 45 of an upper trimming cutter movable in a plane substantially parallel to the bottom of the form to trim the margin of the upper on a continuous line about the toe from one side of the toe to the other side.

50 63. In an upper shaping machine, the combination with means for wiping the marginal portion of the toe of an upper inwardly over a form and for holding it in overwiped position, of a power operated cutter mounted for movement to trim the margin of the upper about the toe while the upper is held by the wiping means.

64. In an upper shaping machine, the combination with end embracing wipers for 60 wiping the marginal portion of the toe of an upper inwardly over a form and for holding the upper with the inner portion of its margin extending transversely of the plane of the wipers, of upper trimming mechanism constructed and arranged to trim the margin

of the upper on a continuous line from one side of the toe to the other side substantially in the plane of the outer face of the wipers.

65. In an upper shaping machine, the combination with end embracing wipers for wiping the marginal portion of the toe of an upper inwardly over a form and for holding the upper with the inner portion of its margin extending transversely of the plane of the wipers, of a cutter arranged to cut 70 from the inner side of said transversely extending margin outwardly therethrough to trim the upper.

66. In an upper shaping machine, the combination with end embracing wipers for wiping the marginal portion of the toe of an upper inwardly over a form to produce an upstanding flange for attachment to the rib of an insole, of a cutter mounted for movement in a plane transverse to said upstanding flange of the upper to trim said flange 80 while the upper is held by the wipers.

67. In an upper shaping machine, the combination with end embracing wipers for wiping the marginal portion of the toe of an upper inwardly over a form to produce an upstanding marginal flange on the upper, of a cutter arranged to cut outwardly through 85 said flange at one side of the toe and then to move about the toe to its other side for trimming the upper.

68. In an upper shaping machine, the combination with end embracing wipers for wiping the marginal portion of the toe of an upper inwardly over a form to produce an 100 upstanding marginal flange on the upper, of a power operated cutter mounted for movement to trim said upstanding flange progressively along the edges of the wipers by a cut beginning at one side of the toe and 105 ending at the other side of the toe.

69. In a lasting machine, the combination with toe embracing wipers for wiping the marginal portion of the toe of an upper inwardly to produce a flange upstanding 110 against the rib of the insole, of a cutter mounted for movement to trim said upstanding flange in predetermined relation to the plane of the insole.

70. In a lasting machine, the combination with toe embracing wipers for wiping the marginal portion of the toe of an upper inwardly to produce a flange upstanding against the rib of the insole, of a power driven cutter having a cutting edge arranged to operate in a plane substantially parallel to the plane of the insole to trim said upstanding flange, and controlling means for positioning said cutter to cut in a plane above the rib of the insole. 115

71. In a lasting machine, the combination with toe embracing wipers for wiping the marginal portion of the toe of an upper inwardly to produce a flange upstanding 120 against the rib of the insole, of a power 125

driven cutter having a cutting edge arranged to operate in a plane substantially parallel to the plane of the insole to trim said upstanding flange, said cutter being movable about the toe to trim said flange progressively, and a member movable with the cutter and arranged to engage the in-

sole to determine the distance from the plane of the insole where the flange is trimmed.

In testimony whereof I have signed my name to this specification.

AUGUSTINE F. LITTLEFIELD.

Certificate of Correction.

It is hereby certified that in Letters Patent No. 1,439,009, granted December 19, 1922, upon the application of Augustine F. Littlefield, of Lynn, Massachusetts, assignor, by mesne assignments, to United Shoe Machinery Corporation, of Paterson, New Jersey, a Corporation of New Jersey, for an improvement in "Mechanism for Use in Shaping Shoe Uppers," an error appears in the printed specification requiring correction as follows: Page 5, line 42, claim 22, for the word "The" read *In*; and that the said Letters Patent should be read with this correction therein that the same may conform to the record of the case in the Patent Office.

Signed and sealed this 6th day of February, A. D., 1923.

[**SEAL.**]

KARL FENNING,

Acting Commissioner of Patents.
